CLAIM

(57) The ornamental design for a dispenser, as shown and described.

DESCRIPTION

FIG. 1 is an isometric view of a front, top, and left side of an ornamental design for a dispenser;

FIG. 2 is a front elevational view of the dispenser of FIG. 1, the left side, right side, and rear elevational views being the same as FIG. 2;

FIG. 3 is a top plan view of the dispenser of FIG. 1;

FIG. 4 is a bottom plan view of the dispenser of FIG. 1;

FIG. 5 is an isometric view of a front, top, and left side of another embodiment of an ornamental design for a dispenser; FIG. 6 is a front elevational view of the dispenser of FIG. 5, the left side, right side, and rear elevational views being the same as FIG. 6;

FIG. 7 is a top plan view of the dispenser of FIG. 5; and,

FIG. 8 is a bottom plan view of the dispenser of FIG. 5.

The broken lines are for the purpose of illustrating environmental structure and form no part of the claimed design.
